UNITED STATES PATENT OFFICE

EDWARD A. KLIEWER, OF RANGER, TEXAS

AUTOMATIC BACK TWIST TOOL FOR WIRE LINES

Application filed September 23, 1929. Serial No. 394,435.

This invention relates to well drilling tools and equipment and particularly to cable drilling and it has for its principal object to provide a device, wholly automatic in its operation designed to replace in a drilling cable the required number of turns which have been taken out during the process of drilling by the twisting of the drilling tools.

Another object of the invention resides in a device of the character specified affording a means of safety for drillers and attendants who are frequently injured by violent whipping of the cable occasioned by releasing the drilling clamps when pulling out tools.

With the foregoing objects as paramount, the invention has particular reference to other objects and advantages as well as its salient features of construction, arrangement of parts and performance, all of which will become manifest as the description proceeds, taken in connection with the accompanying drawings, wherein;

Figure 1 is a perspective view of an improved tool constructed according to the present invention.

Figure 2 is a similar view, showing the invention operatively secured in position.

Figure 3 is a fragmentary view in perspective, showing the operative face of one of the cable engaging slips.

Figure 4 is a sectional view of one of the arms taken axially through the slip, showing the securing means for the latter, and

Figure 5 is a modified form of slip, illustrating a non-frictional bearing surface.

In the cable drilling art, as is generally known to those familiar therewith, operators are exposed to the hazards of entanglement in the lines, resulting in bodily injury or possible death by the whipping action of the cable, and conditions are rendered otherwise difficult to handle since there are no tools by which to remedy the situation other than certain types of clamps which are fixed to the cable and turned by two or more men. These clamps are not wholly practical in themselves in that they are manually operated by the provision of arms which are passed from one man to another in replacing the turns in

the cable. Should one man release his grip on one of the arms, the torque in the cable causes the latter to twist violently, probably striking the operators and inflicting serious injuries.

Accordingly, the present invention comprehends the provision of a tool, manually set but automatic in its function in replacing the turns in the cable preparatory to drilling. It is so designed, that it may replace the standard number of turns in the line by moving the line therethrough a predetermined extent.

The present invention therefore, is comprised primarily of two arms 1, hingedly connected at one end by a threaded pin 2, forming an integral part of an upright post 3, by which the device is held relative to the stand pipe 4 of the well into which the cable 5 passes to operatively suspend the tools in the well. It is not considered necessary to illustrate any of the conventional tools or other equipment of the well, since these are all well known and their relationship with the present invention will be well understood by those familiar with the art.

Intermediate the ends of the arms 1, which by the way are arranged to be operatively locked in parallel relationship by a swing bolt 6, entering the bifurcated end of one of the arms, is an enlargement 7, defining a recessed block adapted to receive a slip 8 of babbitt or other similar material, and which slip has a grooved surface, as shown, each groove corresponding with each strand of the cable.

It is obviously the intent of the invention that the slips 8 be interchangeable, so that a set of slips may be applied to conform to the lay of the line as the latter is passed therethrough. It is understood that standard wire lines are usually left lay. In providing for such interchangeability of the slips 8, a portion of the block 7 is interiorly counter-sunk at *a*, as apparent in Figures 4 and 5 to receive a boss *b* on the slip, which boss is interiorly threaded to receive a bolt 9, provided for securing the slip in position.

It is apparent that the greatest strain

upon the slip 8 is downward and to prevent such strain from displacing the slip, the latter is provided with an integral flange 10 overreaching the upper face of the block 7.

- 5 When the two sections of the block 7 are brought operatively together, the grooves in the slips 8 register to form continuations of the grooves throughout the depth of the opening thereby formed, so that the cable 10 may, without binding, pass freely through, yet causing the cable to be twisted or turned, the extent being determined by a suitable marker on the slip, which will be later referred to.
- 15 While the principal figures in the drawings show the slips 8 as having frictional bearing surfaces preferably, it is not intended that the invention be limited thereto, as apparent in Figure 5, a modification. In 20 this figure, the grooves are formed in the slip as usual, but are recessed to receive balls 11 at spaced intervals and which latter are held by a conformable plate 12, having openings to allow a small part of the balls to protrude, to be engaged by the line 5 as the latter is passed therethrough, to eliminate as much frictional wear as possible. This plate is fixed by set screws 13. Other modifications may be made also, such for instance as rollers, which are full equivalents of the balls shown in Figure 5.

In operation, it is customary in standard drilling to mark the depth of the hole in various ways, such for instance as applying 35 a little white paint to the cable 5 at a point near the top of the pipe 4, or by tying a piece of cord about the line. When this is done, the drilling clamps are released and the cable is wound upon the conventional drilling 40 drum, over the crown block, bringing the tools from the well.

The invention however, is applied only when running in. The driller observes the 45 depth marker as it descends, and through experience, knows the number of turns per foot the line should have and accordingly stops the descent of the tools when the marker reaches a point at a certain number of feet above the pipe 4. Assuming that the 50 cable has two turns to the foot and it is desired to put in twenty four turns. The depth marker is stopped at a point approximately twelve feet above the pipe 4, whereupon the arms 1 of the invention are brought 55 together and locked by throwing the bolt 6 into locking position, receiving the line 5 between the slips 8, which are correspondingly grooved, as aforesaid. Descent of the tools is continued, their weight drawing the 60 cable through the slips until the required number of turns are replaced in the line, and the tools rest upon the bottom of the hole. The invention is not removed until the drilling clamps have been replaced preparatory to drilling, whereupon the bolt 6 is released,

allowing the arms 1 to be moved, to free the line from the slips. Drilling may then be resumed.

A chain 14 is provided to constrain the invention against rotation while the line is 70 being run in accordance with the manner above explained.

The improved device is described and shown in the drawings as being secured to the floor of the derrick. It will be understood 75 that this is not intended as a limitation, as it is obvious that equally effective results can be obtained by affixing the device to the drilling clamps or at any location which will be convenient to carry out the purpose 80 for which it is intended.

Though the invention has been explained with great particularity, the details of the embodiment of the invention herein shown are not to be construed as being limited 85 thereto, as changes in arrangement and substitution of equivalents may be made by those skilled in the art without departing from the spirit or intent of the invention as set forth in the appended claims.

90 What is claimed is:

1. In a back twist tool for cables, a rigid vertical post, substantially horizontally disposed arms having openings therethrough to receive the upper end of the post whereby said arms are pivoted on the post, complementary blocks carried by said arms said blocks having cable engaging spiral grooves of uniform pitch formed to conform with the lay of the preformed cable to impart 100 twisting motion to a cable forced therethrough, means to lock the arms in operative position and means connected to the opposite ends of the arms to prevent rotation of the arms relative to the post.

105 2. In a back twist tool for cables, a vertical post, substantially horizontal arms, means to pivotally connect one end of the arms to the post, means connected to the opposite ends of the arms to prevent rotation of the arms relative to the post, means to lock the arms in operative position and complementary blocks having cable guiding spiral parts of uniform pitch formed to conform with the lay of the preformed cable to impart 110 a twisting motion to a cable forced therethrough.

115 3. In a back twist tool for cables, a vertical post, substantially horizontally disposed arms, means to pivotally connect one end of the arms to the post, means connected to the opposite ends of the arms to prevent rotation of the arms relative to the post, means to lock the arms in operative position, and means carried by the arms to impart a twist 120 to a preformed cable forced therethrough.

125 4. In a back twist tool for cables, a vertical post, substantially horizontally disposed arms, means to pivotally connect one end of the arms to the post, means connected

to the opposite ends of the arms to prevent rotation of the arms relative to the post, means to lock the arms in operative position, and means carried by the arms to impart a twist to a preformed cable forced there-
5 through, said twist imparting means having spiral guides that conform to the lay of the cable and anti-friction cable engaging ele-
ments in the guides.

10 In testimony whereof I affix my signature.
EDWARD A. KLEWER.
